UNITED STATES PATENT OFFICE.

GEORGE W. LYONS, OF NEW HAVEN, CONNECTICUT, ASSIGNOR TO THE LYONS MANUFACTURING COMPANY, OF NEW HAVEN, CONNECTICUT, A CORPORATION OF CONNECTICUT.

CIGARETTE CASE.

Application filed December 29, 1923. Serial No. 683,443.

To all whom it may concern:

Be it known that I, GEORGE W. LYONS, a citizen of the United States, residing at New Haven, in the county of New Haven and 5 State of Connecticut, have invented certain new and useful Improvements in Cigarette Cases, of which the following is a specification, reference being had therein to the accompanying drawings.

10 This invention relates to improvements in cigarette cases and has for its object, among other things, to simplify the structure of this type of mechanism, to increase its efficiency, to so design the parts that they 15 may be more economically constructed and more easily and readily assembled, and produce a cigarette case wherein the movement of the cigarettes may be controlled and discharged therefrom without injury or damage thereto.

To these, and other ends, my invention consists in the new and improved cigarette case, having certain details of construction and combinations of parts, as will be 25 hereinafter described and more particularly pointed out in the claims.

Referring to the drawings, in which like numerals of reference designate like parts in the several figures;

30 Figure 1 is a side elevation of my new and improved cigarette case;

Figure 2 is a sectional view, taken generally upon line 2—2 of Figure 1;

Figure 3 is an enlarged sectional view, 35 taken generally upon line 3—3 of Figure 2;

Figure 4 is also an enlarged sectional view, taken generally upon line 4—4 of Figure 2, and

Fig. 5 is a perspective view of the fol- 40 lower.

In the embodiment of my invention as disclosed herein, 10 designates the body of the case, which is constructed with an outwardly projecting rib 11 upon each of the side walls 45 near the top thereof, a discharge opening 12 near one end of one of the walls, a lever opening 13 also through the same wall and adjacent to said opening, and a lug 14 projecting inwardly from one of the end walls 50 thereof.

The cover 15 also has a rib 16 upon each of the opposite side walls thereof, into each of which projects one of the ribs 11 when the cover is assembled with the body, sub- 55 stantially as shown in Figure 4, and by rea-

son of which the cover has a sliding engagement with the body. A finger clip 17 at one end of the cover provides means by which the cover may be easily manipulated by the fingers.

In one of the side walls of the cover is an opening 18, which is opposite the opening 12 when the cover is in its closed position, substantially as shown in Figure 1, and a cut away portion 19 in the same side wall insures a free movement of the finger plate 20 of the throwing lever 21.

Within the body 10 is fixed an inner plate 22, having thereon a plurality of bosses 23, which rest upon the inside of the bottom of the body and between which is an open space 24. Upon opposite sides of this inner plate are the walls 25, which terminate in the outwardly turned flanges 26 that project into the groove formed on the inside of the ribs 75 11. A rigid support is thus formed for the inner plate. The outer end of the inner plate is held in alignment by the preferably integral finger 27, the upper end of which is sprung under the lug 14, substantially as 80 shown in Figure 4. Thus the side and one end of said plate are in a fixed permanent position without the aid of rivets, solder or other similar securing means.

Integral with one of the walls 25, and preferably formed by bending the stock of one of the flanges 26, is a stop lug 28, which projects upwardly in the path of one end of the cover 15, thus limiting the outward position of said cover relatively to the body. The 90 end of this inner plate opposite to that having the lugs 28 thereon is cut away at 29 and the remainder of the width thereof is provided with a pocket portion 30, which rests upon the bottom of the body and having a curvature substantially the same as that of the cigarette.

The cigarettes are held within the case by a metal strap 31, having a foot portion 32 that projects into the open space 24 and between two of the bosses 23, substantially as shown in Figures 3 and 4. This strap is flexible and terminates in the head 33 of slightly greater width than the body of the strap. Slidably mounted upon this strap, 105 between the inner plate 22 and the cover 15, is a follower 34, which, as shown, is constructed from a single piece of metal having opposite side walls 35, a concave front wall 36 and end walls 37. A spring 38 be- 110

tween this follower and one end of the body 10 exerts its tension so as to move the follower toward that end of the body having the discharge opening 12 therethrough.

5. The case is loaded with cigarettes by sliding the cover outwardly until the end wall 48 thereof engages the stop 28 and then placing the cigarettes between the inner plate 22, and the underside of the strap 31. The 10 first cigarette inserted rests in the pocket of the front wall 36 of the follower.

In Figure 3 the dotted lines illustrate four cigarettes in the relative positions occupied by them when the case is partially filled, the 15 uppermost cigarette of the series being in register with the discharge opening 12.

The cigarettes are ejected from the case by lever mechanism, which comprises an ejecting lever 39 operatively connected with 20 the inner plate 22 by the pivot 40, having an ejector finger 41 at its outer end and a rounded end 42 at the opposite end which rests in a socket in the throwing lever 21. This latter lever is held in a guided relation 25 with the inner plate 22 by the guide pin 43 fixed in said inner plate and projecting through an opening 44 in said lever with a head 45 thereon that lies within the recess 46 in one side of said lever. These levers 30 are movably connected with the inner plate 22 and move within the open space 24 between the inner plate and bottom of the body 10 and have no connection whatsoever 35 with said body, and the guided means for connecting the throwing lever 21 with said plate insures a permanent operative connection 40 between the two levers that will not become separated or disengaged from each other by accidental or other means so as to impair the efficiency of the ejecting mechanism.

Fixed in one end of the throwing lever 21 is a spring 47, which rests against one of the side walls of the body 10 and exerts its 45 tension so as to normally hold the two levers in substantially the position shown in Figure 2, that is, the ejector finger 41 in its retracted position and the finger plate 20 in its outermost position. Pressure applied to 50 the throwing lever 21 through the finger plate 20 rocks the ejecting lever 39 and the finger 41 moves the cigarette in line therewith through the discharge opening 12. As soon as pressure is released upon the lever 55 21, the spring 47 returns the levers to the position illustrated in Figure 2, and the spring 38 advances the follower 34 and presents the next succeeding cigarette in line 60 with the ejecting finger and discharge opening.

Obviously, there are many minor changes and alterations that may be made within my invention, aside from those herein suggested, and I would therefore have it understood that I do not limit myself to the exact

construction herein shown and described, but claim all that falls fairly within the spirit and scope of the appended claims.

Having described my invention, what I claim as new and desire to secure by Letters Patent, is:—

1. In a cigarette case; a body; a cover movably connected therewith; an inner plate connected with said body; and ejector mechanism comprising companion levers 75 movably mounted upon said inner plate and spaced from the body so as to move freely relatively thereto irrespective of the shape or smoothness of the adjacent face of the body.

2. In a cigarette case; a body having an inwardly projecting lug; a cover movably connected therewith; an inner plate connected with said body and held in position at one end by means of an intermeshing 85 engagement with said lug.

3. In a cigarette case; a body; a cover movably connected therewith; and an inner plate connected with said body having a pocket portion at one end thereof in which the cigarette moves while being ejected.

4. In a cigarette case; a body; a cover movably connected therewith; an inner plate connected with said body, held in position in part by means of an intermeshing 95 engagement therewith and in spaced relation with said body by one or more bosses thereon.

5. In a cigarette case; a body; a cover movably connected therewith; an inner plate connected with said body, held in position in part by means of an intermeshing 100 engagement therewith, and in spaced relation with said body by one or more bosses thereon; and ejector mechanism movably 105 and inseparably connected with said inner plate and movable within the open space between said bosses.

6. In a cigarette case; a body having ribs upon the side walls thereof; and an inner plate having walls, parts of which intermesh with 110 said ribs and provide means for holding the inner plate in fixed relation with the body.

7. In a cigarette case; a body having ribs upon the side walls thereof; a cover movably connected therewith; an inner plate having walls, parts of which intermesh with 115 said ribs and provide means for holding the inner plate in fixed relation with the body; and stop means connected with one of said walls for limiting the movement of said cover relatively to said body.

8. In a cigarette case; a body having ribs upon the side walls thereof; and an inner plate having walls with flanges projecting laterally therefrom and into the grooves formed by said ribs, whereby the plate is held in fixed relation to said body.

9. In a cigarette case; a body having ribs 130

upon the side walls thereof; an inner plate having walls, parts of which intermesh with said ribs; and means connected with said plate at one end thereof having an intermeshing engagement with a part connected with said body, whereby said plate is held in fixed relation with said body.

10. In a cigarette case; a body having ribs upon the side walls thereof; an inner plate held in fixed relation with said body by engagement of parts thereon with said ribs and by the engagement of another part with a lug upon the body

11. In a cigarette case; a body; a cover movably connected therewith; an inner plate connected with said body; and ejector mechanism comprising companion levers movably connected with said inner plate, one of said levers having a pivotal connection with the inner plate and the other having a guided connection therewith by means of a pin fixed in said plate that projects through an opening in the lever and having means thereon to hold the lever from movement parallel with its axis.

12. In a cigarette case; a body; a cover movably connected therewith; an inner plate connected with said body; and ejector mechanism comprising companion levers movably connected with said inner plate, one of said levers having a pivotal connection with the inner plate and the other having a guided connection therewith by means of a pin fixed in said plate that projects through an opening in the lever and having means thereon to hold the lever from move-

ment parallel with its axis, said means being flush at one end with the face of the last mentioned lever.

13. In a cigarette case; a body; a cover movably connected therewith; an inner plate connected with said body; ejector mechanism comprising companion levers movably connected with said inner plate, one of said levers having a pivotal connection with the inner plate and the other having a guided connection therewith by means of a pin fixed in said plate that projects through a recessed opening in the lever and having a head thereon that lies within the recess of said opening to hold the lever from movement parallel with the axis of the pin.

14. In a cigarette case; a body; a cover movably connected therewith; a strap fixed in said body at one end and projecting to the opposite end thereof that holds the cigarettes in alignment with the case; a follower having an opening therethrough for said strap; and spring means for actuating said follower in one direction.

15. In a cigarette case; a body; a cover movably connected therewith; a strap fixed in said body at one end and projecting to the opposite end thereof that holds the cigarettes in alignment with the case; and a follower having means connected therewith for preventing lateral movement of said strap in relation thereto.

In testimony whereof, I have hereunto affixed my signature.

GEORGE W. LYONS.
